UNITED STATES PATENT OFFICE.

CEDRIC PUTNAM SIBLEY, OF DETROIT, MICHIGAN.

FASTENER FOR PAPERS AND OTHER MATERIALS.

1,394,123.

Specification of Letters Patent.

Patented Oct. 18, 1921.

Application filed August 7, 1920. Serial No. 401,934.

To all whom it may concern:

Be it known that I, CEDRIC PUTNAM SIBLEY, a citizen of the United States, residing at Detroit, in the county of Wayne and State 5 of Michigan, have invented a certain new and useful Improvement in Fasteners for Papers and other Materials, of which the following is a full, clear, and exact description.

10 The object of this invention is to improve the construction of the well-known "Challenge" eyelet, rivet or paper-fastener, forming the subject of Patent No. 358,225, granted February 22, 1887, whereby an equally 15 good, if not superior article is produced at a very considerable saving in stock.

The invention consists of an eyelet or similar fastener formed from a blank having a solid center and longitudinally slotted ends, 20 and provided with excisions oppositely arranged relatively to the solid center, so that when the eyelet is formed there will be a barrel portion closed at one end and having a flange at its other end formed from the 25 slotted ends, the excisions permitting the formation of a cylindrical barrel divided longitudinally by the slits and adapted to be collapsed in the setting of the eyelet, as I will proceed now to explain and finally 30 claim.

Distinguishing the present invention from the "Challenge" eyelet, it is to be noted that in the former the blank is rectangular and has its ends slotted to form a longitudinally 35 divided barrel and a base flange, with a solid center having opposite excisions, and little or no appreciable scrap, while the latter is cut out or stamped in star shape from a strip, at considerable loss of stock as scrap.

40 In the accompanying drawings illustrating the invention, in the several figures of which like parts are similarly designated, Figure 1 is a plan view of the blank showing the excisions alongside. Fig. 2 is a plan view of the slotted blank. Fig. 3 is an elevation of the eyelet, and Fig. 4 is a top plan view thereof. Fig. 5 is an elevation of the 45 eyelet in process of setting. Fig. 6 is a top plan view, and Fig. 7 is a bottom plan view thereof.

In the manufacture of this eyelet or fastener, a strip 1 of suitable metal of rectangular shape, has its opposite ends slotted longitudinally, as at 2, to form two sets of strips or fingers 3, of like number and preferably three, leaving a solid intermediate

portion 4. Opposite this solid portion excisions 5 are made in the edges of the strip. The blank thus prepared is then drawn up or otherwise formed into a cylindrical or 60 tubular barrel portion 6, one end of which is closed by the solid portion 4, the strips 3 forming the barrel and a laterally extending flange or base 7 at the open end and opposite the closed end formed by the solid portion A. 65 The excisions 5 facilitate the shaping of the barrel and the subsequent collapsing thereof in setting the eyelet.

In use, the closed end of the barrel is passed through the papers or other objects 70 to be fastened together, so that the flange abuts against the outer object, and then the barrel is collapsed so as to spread out the strips 3 laterally and flatten them out upon the opposite outer object. Figs. 5 and 6 75 indicate the beginning of the collapsing operation, while Fig. 7 shows the eyelet set.

Thus a many-strip or finger article is formed, with a minimum of waste or scrap, as indicated by the small pieces 8, Fig. 1, cut 80 from the blank, and hence the eyelets may be very economically manufactured.

The invention is susceptible of variations within the principle and scope of the claims following.

85 What I claim is:

1. A fastener for papers and other objects, having one end closed and the remainder divided longitudinally into strips of even number and forming a substantially cylindrical 90 collapsible barrel and a laterally spread flange or base, there being excisions in the barrel adjacent to the closed end to facilitate the collapsing of the barrel.

2. A fastener for papers and other objects, having a closed end and a longitudinally slotted barrel composed of a plurality of strips or fingers of even number, said strips or fingers terminating in laterally extended portions forming a flange, said barrel having 100 oppositely arranged excisions adjacent to the closed end to facilitate the setting of the fastener.

3. A fastener for papers and other objects, having a closed end and a longitudinally slotted barrel composed of a plurality of strips or fingers of even number, there being cut out portions between the closed end and adjacent parts of the strips or fingers, said strips or fingers terminating in laterally extended portions forming a flange. 110

4. The art of making hollow collapsible

- fasteners for papers and other objects, with little waste or scrap, same comprising slitting a metal blank longitudinally from opposite ends in an inward direction and toward a solid middle portion so as to provide a plurality of strips, excising portions of the blank adjacent to the solid middle portion, bending said strips downwardly from the solid middle portion in substantially parallel relation to form the hollow portion of the fastener, and outwardly flanging the free ends of the strips to form a laterally extending flange.
5. The art of making tubular collapsible paper fasteners, with little waste or scrap, same comprising slitting a rectangular blank

longitudinally from its ends inwardly toward a solid middle portion so as to provide a plurality of strips, cutting out small portions from its sides next to its solid middle portion, and then forming the blank into a tubular portion having one end closed and the other open, and spreading the ends of the strips at the open end of the barrel into a laterally extending base flange. 25

In testimony whereof I have hereunto set my hand this 20th day of July, A. D. 1920.

CEDRIC PUTNAM SIBLEY.
